UNITED STATES PATENT OFFICE

THOMAS W. MILLER, OF ASHLAND, OHIO, ASSIGNOR TO THE FAULTLESS RUBBER COMPANY, OF ASHLAND, OHIO, A CORPORATION OF OHIO

SPONGE RUBBER

Application filed January 30, 1929. Serial No. 336,277.

My invention relates to sponge rubber articles, and to a process of making the same, and the principal object of my invention is to provide new and improved articles, and a new and improved process, and in the drawings accompanying this specification and forming a part of this application I have shown, for purposes of illustration, certain forms which my invention may assume. In these drawings:

Figure 1 is a perspective view illustrating two slabs of vulcanized sponge rubber,

Figure 2 is a perspective view of a composite slab formable from the two slabs of Figure 1,

Figure 3 is a perspective view of a bath sponge formable from the composite slab of Figure 2,

Figure 4 is a perspective view of a second composite slab formable from the slabs of Figure 1,

Figure 5 is a perspective view of a bath sponge formable from the composite slab of Figure 4,

Figure 6 is a perspective view of a third composite slab formable from the slabs of Figure 1,

Figure 7 is a perspective view of a bath sponge formable from the composite slab of Figure 6,

Figure 8 is a perspective view of a fourth form of bath sponge formable from the slabs of Figure 1,

Figure 9 is a perspective view of a powder puff constructed according to my invention,

Figure 10 is a section of the line 10—10 of Figure 9,

Figure 11 is a perspective view of another form of powder puff also constructed according to my invention, while

Figure 12 is a section of the line 12—12 of Figure 11.

Describing my invention as it is applied to bath sponges, I form two slabs of vulcanized sponge rubber 21 and 22 as shown in

Figure 1, each in a suitable mold and therefore covered on all sides with a smooth skin 23 enclosing a sponge rubber body 24, then I trim the slabs 21 and 22 along the dotted lines 25 to remove the peripheral margins 26, 50 and then I split the slabs 21 and 22 along the center lines 27. Obviously this gives me four half slabs, two half slabs 28 from the slab 21 and two half slabs 29 from the slab 22, each half slab showing cut sponge on its 55 four marginal edges and on one face, and showing skin on its other face. Next I take two of these half slabs 28 and 29 and place them together back to back, that is with the two skin faces abutting, and I secure these two half slabs together in this position in any suitable manner, for example by cementing them together with a suitable rubber cement. Obviously at this point I produce a composite slab equal in thickness to either of the original slabs but with the skin of the two faces of the original slab shifted to the center to act as a stiffener, and with cut sponge on all exposed sides and faces, and accordingly in this way I have produced a sponge sheet having cut sponge on all exposed surfaces, and I have done so without the waste which would be incurred by merely trimming all surfaces of the slabs 21 and 22, yet at the same time I have produced a 75 sponge sheet which because of the center stiffening resulting from the retention of the skins and the placing of the two skins in a position abutting each other actually is greatly superior at least for many purposes. 80

At the same time still another advantage and result can be obtained; if the two slabs 21 and 22 are formed of different sponge rubbers, and if the composite slab is formed of one half slab 28 from the slab 21 and one half slab 29 from the slab 22, then the composite slab will be of one sponge rubber on one face and of another sponge rubber on the other face. For example, if the slab 21 is green color sponge rubber of coarse texture and 85

the slab 22 is blue color sponge rubber of fine texture then by combining a half slab 28 from the slab 21 and a half slab 29 from the slab 22 there will result the composite slab 30 shown in Figure 2 and having cut sponge on all surfaces, having one face of blue color sponge rubber of fine texture, having the other face of green color sponge rubber of coarse texture, and having centrally 10 the strengthening of the abutting skins 23.

Obviously at this point the composite slab 30 may be cut as indicated by the dotted lines 31 to form a plurality of bath sponges 32 as shown in Figure 3, each having cut sponge on all surfaces, each strengthened by the centrally positioned skins 23, each having one portion 33 colored green and of coarse texture for rough cleansing, and each having a portion 34 colored blue and of fine 20 texture for more delicate cleansing.

Under certain circumstances it may be desirable to stiffen the article additionally to the stiffening resulting from the center positioning of the skins 23, and in such case I may 25 interpose between the two half slabs 28 or 29 a sheet of rubber 35 or 36 as shown in the composite slabs 37 and 38 of Figures 4 and 6, and in such event I may form the rubber sheets 35 and 36 with utilitarian projections, for example, the rubber sheet 35 30 with a plurality of teeth 39 projecting along each of the longitudinal edges of the composite slab 31, and the rubber sheet 36 with a plurality of tabs 40 projecting along each of the longitudinal edges of the composite slab 38, so that when the composite slabs 37 and 38 are cut along the lines 41 and 42 there will result the bath sponges 43 and 44 shown respectively in Figures 5 and 7 and 40 each similar to the bath sponge 34 of Figure 3 but provided with the central stiffening sheet 35 or 36 and with the functional projection extending from the sheet 35 or 36, the sponge 43 with the points 39 suitable for various purposes such as cleaning finger 45 nails, and the sponge 44 with the tab 40 by which the sponge may be hung upon a suitable hook.

In some instances it may be desirable to 50 provide a plurality of utilitarian projections on each individual bath sponge, and in such case I may cut the one half slabs 28 and 29 into blocks before they are assembled back to back and then assemble each pair of blocks back to back to secure the bath sponges 45 of Figure 8 wherein there is interposed between the green and blue portions 46 and 47 a sponge rubber sheet 48 having a utilitarian projection on each edge, the points 39 on each longitudinal edge and a tab 40 on each end edge. Of course it will be understood 55 that the projections may differ on the two sides, also on the two ends, and also that where only two different projections are required that result may be accomplished with-

out cutting the half slabs into individual blocks, for example, the half slabs will be cut into blocks large enough for four bath sponges, two each way, and one type of projection provided on one pair of opposite edges of the inserted sheet and the other type on the other pair of opposite edges of the inserted sheet, whereupon each individual bath sponge will be provided on one side with one type of projection and the one end 70 with the other type of projection. 75

Of course it will be understood that the sponges of Figures 5 and 7 and 8 may be formed of one sponge rubber or of two sponge rubbers, whichever may be desired, 80 in the same manner as described in connection with the sponge of Figure 3.

In the foregoing I have considered my invention as applied to bath sponge, but it may be applied to other articles, and by way of 85 illustration I have shown my invention in Figures 9 through 12 as applied to a powder puff, in Figures 9 and 10 to a powder puff 49 comprising an upper blue portion 50 and a lower green portion 51 both of fine texture, strengthened only by the skin 52, and provided with a thin rubber tape 53 inserted between the two portions 50 and 51 at one corner thereof to form a tab by which the puff 49 may be handled, while in Figures 11 and 12 I have 95 shown a puff 54 comprising a lower coarse texture green portion 55 and an upper fine texture blue portion 56 between which is interposed a stiffening sheet 57 provided with a tab 58. 100

Of course it will be obvious to those skilled in the art that the various features enumerated in connection with the bath sponge may also be applied to the powder puff, also that some or all of the features herein disclosed 105 may be applied to various other sponge rubber articles, and that in one form or another the process herein above disclosed will be utilized in the manufacture not only of bath sponges and powder puffs but of a wide variety of sponge rubber articles, accordingly it will be obvious that the embodiments of my invention herein disclosed are illustrative only, that my invention is not limited to those particular embodiments which I have disclosed herein. 110

I claim:

1. The method of forming a sponge rubber article which comprises uniting two pieces of sponge rubber each formed by splitting a sponge rubber slab and from the abutting face of at least one of which the skin has not been removed. 120

2. The method of forming a sponge rubber article which comprises uniting, against the two sides of a rubber sheet, two pieces of sponge rubber each formed by splitting a sponge rubber slab and from the abutting face of at least one of which the skin has not been removed. 125 130

3. The method of forming a sponge-rubber article, which comprises: splitting a sponge-rubber slab, to form a split-slab sponge-rubber board, and superposing said split-slab board and another sponge-rubber board, with skin on at least one of the abutting surfaces, to form an intermediate reinforcement. 70
4. The method of forming a sponge-rubber article, which comprises: splitting a sponge-rubber slab, to form a split-slab sponge-rubber board, and superposing said split-slab board and another sponge-rubber board, with skin on at least one of the abutting surfaces, to form an intermediate reinforcement, and with cut sponge on at least one of the opposite faces. 80
5. The method of forming a sponge-rubber article, which comprises: splitting sponge-rubber slab, to form split-slab sponge-rubber boards, and superposing two such boards, with skin on at least one of the abutting surfaces, to form an intermediate reinforcement, and with cut sponge on at least one of the opposite faces. 85
- 25 6. The method of forming a sponge-rubber article, which comprises: splitting a sponge-rubber slab, to form a split-slab sponge-rubber board, and superposing said split-slab board and another sponge-rubber board, with skin on both the abutting surfaces, to form an intermediate reinforcement, and with cut sponge on at least one of the opposite faces. 90
7. A sponge-rubber article, comprising two sponge-rubber boards, superposed one on the other, at least one being a split of a sponge-rubber slab, and at least one having skin on its abutting face, to provide an intermediate reinforcement. 100
8. A sponge-rubber article, comprising two sponge-rubber boards, superposed one on the other, at least one having skin on its abutting face, to provide an intermediate reinforcement, and at least one having cut sponge on its face opposite its abutting face. 105
9. A sponge-rubber article, comprising two sponge-rubber boards, superposed one on the other, at least one being a split of a sponge-rubber slab, at least one having skin on its abutting face, to provide an intermediate reinforcement, and at least one having cut sponge on its face opposite its abutting face. 110
- 50 10. A sponge-rubber article, comprising two sponge-rubber boards, superposed one on the other, each being a split of a sponge-rubber slab, at least one having skin on its abutting face, to provide an intermediate reinforcement, and at least one having cut sponge on its face opposite its abutting face. 115
11. A sponge-rubber article, comprising two sponge-rubber boards, superposed one on the other, at least one being a split of a sponge-rubber slab, each having skin on its abutting face, to provide an intermediate reinforcement, and at least one having cut sponge on its face opposite its abutting face. 120
- 65 12. A sponge-rubber article, comprising two sponge-rubber boards, superposed one on the other, each being a split of a sponge-rubber slab, each having skin on its abutting face, to provide an intermediate reinforcement, and each having cut sponge on its face opposite its abutting face. 125

In testimony whereof I hereunto affix my signature.

THOMAS W. MILLER. 75
